TABERNACLE SAFE HAVING A REVOLVABLE
INNER CASING

Ellen F. Halter, Philadelphia, Pa.

Application October 10, 1944, Serial No. 557,985.

1 Claim. (Cl. 312—33)

1 This invention relates generally to altar tabernacles for the safe storage of the various sacred vessels and other altar appointments which are periodically employed in connection with church services, and more particularly to an improved construction of a tabernacle safe which lends itself to all rubrical and liturgical requirements.

Among the principal objects of the present invention is to provide a freestanding tabernacle safe having a revoluble interior which is adapted to be locked in any one of several different closed positions to thereby selectively present to view differently ornamented panels, each of which latter serves to close a single access opening to the interior of the tabernacle.

Still another object of the present invention is to provide a construction of tabernacle safe having a single opening to the interior as aforesaid which is adapted to be positively and automatically locked against unauthorized access to the valuables contained in the tabernacle merely upon rotation of the interior member into any one of its several closed positions.

A still further object is to provide a self-locking arrangement for the tabernacle in which the key for the lock serves only to unlock the revoluble inner member for rotation into a selected closed or open position, self-locking of the said inner member in said position being effected automatically upon release or removal of the key from its lock.

Still other objects are to provide a simple, inexpensive and yet exceedingly effective tabernacle safe construction, the several parts of which are adapted to be easily fabricated and readily assembled in the form of a complete unit which lends itself admirably to the application of external ornamentation and furnishings such as are typical in altar tabernacles.

Other objects and advantages of the present invention will appear more fully hereinafter; it being understood that the present invention consists substantially in the combination, construction, location and relative arrangement of parts, all as will be described in detail hereinafter; as shown in the accompanying drawings and as finally pointed out in the appended claim.

In the said accompanying drawings, which are illustrative of a preferred form and construction of the tabernacle of the present invention:

Figure 1 is a front elevational view of the tabernacle showing the opening to the interior thereof closed against access therethrough;

Figure 2 is a vertical sectional view of the tabernacle;

Figure 3 is a horizontal sectional view taken on the line 3—3 of Figure 1;

Figure 4 is a horizontal sectional view also taken on the line 3—3 of Figure 1, but showing the interior thereof rotated into position to provide access into the interior of the tabernacle; and

Figure 5 is a partial view shown in section on an enlarged scale taken on the line 5—5 of Figure 4;

Referring now to the drawings, it will be observed that the tabernacle of the present invention essentially consists of a freestanding external casing 10 within the interior of which is mounted a revoluble drum-like member 11 for rotation about the central vertical axis of the tabernacle. As most clearly appears in Figures 1 and 2, the external relatively stationary casing 10 includes a generally circular supporting base 12 having an annular flange 13 extending upwardly from the marginal edge of the central part 14 of said supporting member. This annular flange 13 is internally rabbeted, as at 15, to provide a shouldered seat for reception of the lower edge of the cylindrical body member 16 suitably formed of sheet metal or the like.

Fitted to the upper edge of this cylindrical body member 16 is an annular member 17 of the cross-section best shown in Figure 2 to provide a depending portion 18, an upwardly extending portion 19 and an inwardly extending radial flange portion 20. The depending portion 18 of the ring member 17 closely embraces the upper edge of the cylindrical body member 16 and is secured thereto in any suitable manner, as by a plurality of circumferentially spaced cap bolts 21, the shanks of which threadedly engage tapped washers 22 which are brazed or otherwise secured to the inner surface of the body member 16. The lower edge of this body member is similarly secured to the annular flange 13 of the base or supporting member 12.

Fitted within the upper section of the annular ring 17 is a dome or canopy 23 having an annular cylindrical portion 24, which is secured to the upwardly extending portion 19 of the ring member 17 by a plurality of circumferentially spaced cap bolts 21 with its lower edge resting upon the radial flange or rib 20 of said ring member. The ring member 17 thus serves to secure together in assembled relation the external cylindrical body member 16 and the upper dome or canopy 23; and it will further be observed that these assembled parts, together with the base or supporting member 12, provide a complete en-

closure for the tabernacle, access to the interior of which may be had only by way of an opening 25 (see Figure 1), which is provided through the wall of the cylindrical body member 16, this opening being preferably of the rectangular shape shown and of a width somewhat less than one-quarter the total circumference of the external body.

The inner revoluble drum assembly 11 essentially consists of a sheet rolled into cylindrical form with the opposite vertical edges 26 and 27 (see Figure 4) spaced from each other for a distance approximately equal to the width of the opening 25 in the outer shell, the cylindrical body of the inner drum so formed being fitted with a top closure plate 28 and a bottom closure plate 29. These latter plates are respectively provided with annular flanges 30—31 which snugly fit within the interior of the cylindrical shell of the internal drum 11 and are suitably secured thereto as by brazing or otherwise. The inner surfaces of the top and bottom closure plates 28 and 29 of the internal drum are preferably respectively provided with upper and lower surface boards 32 and 33 secured in place by the screws 34.

The top closure plate 28 of the inner drum assembly is centrally provided with an apertured boss 35 within which is non-rotatably fitted a vertically extending bearing pin or shaft 36. Similarly, the bottom closure plate 29 is centrally provided with an apertured boss 37 within which is non-rotatably fitted a bearing pin or shaft 38 extending in opposite direction from, but in axial alignment with the upper pin 36.

Suitably provided within the top of the dome 23 is an upper support or bearing 39 within which is received the free end of the bearing pin 36. This bearing support 39 may be formed as a separate element for rigid securing to the dome 23, as by brazing or by the use of suitably securing elements, or it may be cast as an integral part of the dome.

The base or supporting member 14 for the tabernacle is in turn centrally provided with an apertured boss 40 for reception of the lower bearing pin 38, it being noted in this connection, as most clearly appears in Figure 2, that the lower boss 37 of the inner drum assembly is in direct engagement with and rests upon the boss 40 of the supporting base, the axially aligned bearing pins 36 and 38 serving to maintain the inner drum assembly coaxial with respect to the external body 10 while permitting rotation of the inner drum with respect to said outer body. It will be noted further that the internal drum is of a diameter only slightly less than that of the external body so that waste space therebetween is reduced to a minimum.

It will be understood, of course, that the internal drum 11 constitutes the actual receptacle for the sacred vessels and the like which are to be stored within the tabernacle safe, the board 33 serving as the floor of this inner receptacle. As most clearly appears in Figures 3 and 4, this floor board 33 is provided with a radially extending portion 41 which snugly fits within the space provided between the vertically extending edges 26 and 27 of the inner drum shell and extends outwardly therethrough into close proximity with the internal surface of the shell 16 of the external casing 10. The outer free edge of this radially extending portion 41 of the floor board 33 is in the form of a circular arc, the diameter of which is only slightly less than that of the external shell 16, in consequence of which the said radially

extending portion 41 of the floor board 33 bridges the space between the concentric shells 11 and 16 and so precludes the possibility of any small article dropping into said space when the internal drum is rotated into the position shown in Figure 4 and in which position, of course, the safe is open for access to the interior thereof. If desired, the ceiling board 32 of the internal drum may be similarly provided with a radially extending portion to bridge the gap between the inner and outer cylindrical shells of the tabernacle.

As most clearly appears in Figures 1, 2 and 4, the lower plate 29 of the internal drum assembly 11 is provided adjacent its marginal edge with a plurality of circumferentially spaced apertures or recesses 42 into any one of which is adapted to be projected the bolt 43 (see Figure 5) of a lock mechanism designated generally by the reference numeral 44. This lock mechanism 44 is preferably of that conventional type in which the bolt 43 is normally spring-pressed into its locking position, as shown in Figure 5, the bolt being adapted for retraction by means of a suitable key (not shown) fitted into the keyhole 45 of the tumbler cylinder 46 suitably fitted in the annular wall of the supporting base 12 of the tabernacle structure. Preferably, and for convenience, the lock mechanism 44 is located centrally below the door opening, as shown in Figure 1, although, of course, it may be located at any other suitable point about the circumference of the supporting base 12. It will be understood that the locking arrangement is such that upon insertion of the key into the lock and operation thereof, the bolt 43 may be retracted against the action of the biasing spring 47 to thereby withdraw it from the particular aperture or recess 42 in the base of the internal drum with which it may have been engaged, the internal drum being then free for rotation about its vertical axis. Upon release of the key or upon withdrawal thereof from the lock, the lock bolt 43 is immediately urged into locking position under the influence of the biasing spring 47 with the result that when the internal drum is rotated to present any one of the recesses 42 in registry with the bolt, the latter immediately enters such recess to lock the internal drum in the particular locked position determined by that one of the recesses 42 which is so engaged by the bolt 43 of the lock.

As most clearly appears in Figure 4, the lock bolt 43 is shown in engagement with that one of the recesses (designated 42*) for locking the internal drum in a position wherein the opening in the wall of the internal drum assembly is in registry with the opening 25 of the external drum, the tabernacle safe being then open for access to the interior thereof. In order to lock the tabernacle safe closed against such access, the lock 44 is actuated to retract the spring-pressed bolt 43, following which the internal drum is manually rotated about its vertical axis to present one or the other of the remaining bolt recesses 42 in registry with the bolt. To effect this rotation, it is merely necessary to engage and exert pressure against whatever portion of the drum is available through the access opening 25 in the outer casing 10. Automatically, as a selected one of the remaining recesses 42 is brought into registry with the locking bolt 43, the latter snaps into engagement with such selected recess to lock the tabernacle in closed position, the wall of the internal drum 11 being extended in such case across the opening 25 to close off the same, as shown in Figures 1 and 3.

It will be noted that in the construction shown, the internal drum 11 may assume any one of three different safe locking positions, each of these positions being determined, of course, by the particular one of the bolt engaging recesses 42 which is engaged by the bolt 43. This arrangement makes it possible to present to view through the opening 25 in the wall of the external shell 10 of the tabernacle different ornamented panels, each of which, of course, serves the primary function of sealing the interior of the tabernacle to unauthorized access thereto. These ornamental panels may be directly embossed in the external surface of the inner drum 11 or they may be detachably secured thereto in the form of suitably inscribed sheets 48 represented by the dotted lines in Figures 3 and 4 suitably held in position between pairs of vertically extending ribs 49 formed upon or carried by the internal drum 11. These ornamental panels greatly enhance the attractiveness of the tabernacle inasmuch as a different suitably ornamented panel may be presented to view through the opening 25 in the outer shell of the tabernacle as the occasion warrants.

It will be understood, of course, that all of the exposed surfaces of the tabernacle as constructed in accordance with the principles of the present invention, including the internal surfaces of the inner revolvable drum, may be covered or draped with any suitable materials in keeping with the ecclesiastical surroundings for the tabernacle, without in any way affecting its primary utilitarian function as a safe. Also, the top or dome of the tabernacle may be suitably ornamented as desired, as is illustrated by way of example in the drawings wherein a cross is shown secured to the top of the dome. In the construction illustrated, the cross is provided with a shank or stem 49 which threadedly engages, as at 50, the upper bearing support 39.

It will be understood, of course, that the present invention is susceptible of various changes and modifications which may be made from time to time without departing from the general principles or real spirit of the present invention, and it is accordingly intended to claim the same broadly, as well as specifically, as indicated in the appended claim.

50

What is claimed as new and useful is:

In a tabernacle safe, a stationary main outer

casing of substantially cylindrical form having closed top and bottom ends and a rectangular opening in the side wall thereof, said top and bottom ends of said casing being respectively 5 provided with coaxial journal bearings, a revolvable inner casing of cylindrical form disposed concentrically within said outer casing and having oppositely extending trunnions respectively journalled in said bearings, said inner casing being 10 closed at the top and bottom ends thereof and having an opening in the side wall thereof adapted to be brought into registry with said side wall opening in the outer casing, said inner casing being further provided with a floor having an 15 extension projecting radially outwardly of the side wall opening thereof into close proximity to the cylindrical wall of the main outer casing, a spring-pressed detent disposed between adjacent closed ends of said concentric casings, said 20 detent being mounted upon one of said adjacent closed ends interiorly of said outer casing for automatic engagement with any one of several circumferentially spaced detent seats formed in the other of said adjacent closed ends whereby upon 25 rotation of said casing said detent seats may be selectively engaged by said detent to lock the inner casing in a selected position relatively to said outer casing, and a key-operated lock mounted upon the side wall of the outer casing for retracting said detent from its engaged seat to permit rotation of the inner casing into a different position, the circumferential spacing of the detent seats being such as to close the interior of the 30 safe against access thereto in all but one of said locked positions of the inner casing.
